Inventor:

George D. Woodworth.

GEORGE D. WOODWORTH, OF CHICAGO, ILLINOIS.

Letters Patent No. 83,232, dated October 20, 1868.

IMPROVEMENT IN STOVE-GRATES.

The Schedule referred to in these Letters Patent and making part of the same.

To all whom it may concern:

Be it known that I, GEORGE D. WOODWORTH, of Chicago, in the county of Cook, and State of Illinois, have invented a new and useful Improved Stove-Grate; and I do hereby declare and make known that the following is a full, clear, and exact description of the same, reference being had to the accompanying drawings, and the letters and figures marked thereon, which form part of this specification.

My said invention consists in constructing a stove-grate, having a horizontal rotating or reciprocating movement upon its bed, and also a revolving movement upon trunnions or lugs, with an independent rotating or reciprocating centre, which may or may not be provided with teeth, and which may or may not be provided with a stirrer, as hereinafter more fully explained.

The object of this feature of my invention is to produce a grate whereby the clinkers or semi-metallic substances, produced by the combustion of hard coal, may be ground out and removed from the grate by the action of a device operating at the point where said clinkers are most apt to collect, without grinding out or shaking out the coal lying upon the main part of the grate.

My said invention further consists in constructing the teeth or grate-bars, which project from the circular or outer rim of the grate inwards towards the aforesaid rotating centre, of a triangular form, having their base upon the outer rim and their apex pointing towards the said centre, and in providing said teeth or bars with slots or openings through the same, whether said teeth slope down towards the centre in one inclination, or with two inclines, one lying below and inside the other, or with one incline and a horizontal member, this feature being, in fact, wholly irrespective of the configuration of the said teeth, as seen in a side view.

The object of this feature of my invention is to secure the teeth to the rim by a broad and strong base, to give strength, and at the same time make the exterior part or portion of the grate as open as possible, to allow the ashes to fall through the grate readily and to insure an abundant draught of air through the outside portions of the mass of coal in the fire-pot, to cause the fire to burn with the intensity desired.

My said invention further consists in constructing the extreme circumference of the outer rim of the grate with a sharp or narrow edge, so that when pieces of coal fall in between said rim and the enclosure of the stove, and prevent the grate from being shaken or moved, the said edge will cut or break the pieces of coal so lodged into small pieces, which will readily drop or get free from such position.

To enable those skilled in the art to understand how

to construct and use my said invention, I will proceed to describe the same with particularity, making reference in so doing to the drawings aforesaid, in which—

Figure 1 represents a plan or top view of my improvement;

Figure 2 is a cross-section through the outer rim; and

Figure 3 is a vertical central section of the grate, taken at the line *z* in fig. 1.

Similar letters of reference denote the same parts of the said invention in the different figures.

A represents the circular rim or circumference of the grate, and B B the lugs or trunnions upon which it is made to revolve when desired; an angular bit, B', upon one of the said trunnions projecting out, whereby a suitable wrench or handle may be applied to the grate for that purpose, said grate resting upon a suitable horizontal bed, so as to be moved or rotated from side to side, as desired.

Projecting inward and downward from the said rim are arms C, which join at the centre, and form the support for a vertical box or bearing, D, in which a central disk or spur, E, is supported upon a rotating shaft, F, as is clearly seen in fig. 3.

Exterior to said box D, a vertical arm, G, is attached to the rotating centre E, in the lower end of which, and of the shaft F, holes, *g f*, are made, in which a rod may be inserted when it is desired to give the said centre, E, an independent rotation within the grate. The said centre, E, may be provided with the teeth *d*, or their equivalent, or the same may be a plain disk, without teeth or projections, although I consider the toothed form the more desirable and effectual form.

To render the said independent rotating centre, E, still more efficacious, if desired, a vertical flange, H, may be formed or secured upon the top of the centre, E, as shown, which serves to give a greater shaking or agitation to the clinkers when the centre is rotated or vibrated, causing said clinkers to be broken between the centre and the points of the teeth *b*, when the same readily fall through the annular space, between said centre and the teeth *b*.

To the said outer rim, the teeth or bars, *b*, are attached in the manner shown, having the triangular openings through the same, marked *e*, thus rendering said teeth strong, and at the same time open, to permit the ashes to fall through and the draught to ascend, as desired.

Upon the outer edge of the rim A, a sharp or thin edge, *a*, is formed, which is designed to be thin enough so that the same will operate to break the coal-lumps in pieces, as aforesaid, and yet strong enough to resist the pressure of the coal thereupon.

Having described the construction and operation of

my invention, I will proceed to specify what I claim, and desire to secure by Letters Patent.

1. I claim the combination of the rotating independent centre E, whether provided with teeth, d, or not, with a grate, A, arranged to operate substantially in the manner herein described.

2. I claim, in combination with the rotating centre, E, a stirrer or flange, H, to operate substantially as and for the purposes set forth.

3. I claim constructing the teeth b with slots, c, substantially in the manner and for the purposes herein specified.

4. I claim providing the rim A with a wire edge, a, as and for the purposes shown and described.

GEORGE D. WOODWORTH.
